Primary Examiner — Karen E Kearney*Assistant Examiner* — Cary M Robinson(74) Attorney, Agent, or Firm — Cantor Colburn LLP(57) CLAIM

I claim, the ornamental design for a display screen or portion thereof with icon, as shown and described.

DESCRIPTION

FIG. 1 is a front view of a display screen or portion thereof with icon showing my new design; and,

FIG. 2 is a front view of another embodiment of a display screen or portion thereof with icon showing my new design. The broken lines are for environmental purposes only and form no part of the claimed design.
